DESIGN FOR A TEXTILE FABRIC

Curt Erwin Forstmann, Montclair, N. J.

Application October 29, 1934, Serial No. 53,807

Term of patent 3½ years

To all whom it may concern:

Be it known that I, Curt Erwin Forstmann, citizen of the United States, residing at Montclair, in the county of Essex and State of New Jersey, have invented a new, original and ornamental Design for Textile Fabric, of which the following is a specification, reference being had to the accompanying drawing, forming part thereof.

In the drawing the sole figure of which is a plan view of a piece of the textile fabric embodying the design of the present invention, the cloth depicted is of a single color.

I claim:

The ornamental design for a textile fabric as shown and described.

CURT ERWIN FORSTMANN.
